US00D854037S

(12) **United States Design Patent** (10) Patent No.: **US D854,037 S**
(45) Date of Patent: ** *Jul. 16, 2019

(54) **DISPLAY SCREEN OR PORTION THEREOF WITH GRAPHICAL USER INTERFACE**

(71) Applicant: **STATE FARM MUTUAL AUTOMOBILE INSURANCE COMPANY**, Bloomington, IL (US)

(72) Inventors: **Sara Maier**, San Jose, CA (US); **Neil Stoeckle**, San Francisco, CA (US)

(73) Assignee: **STATE FARM MUTUAL AUTOMOBILE INSURANCE COMPANY**, Bloomington, IL (US)

(*) Notice: This patent is subject to a terminal disclaimer.

(**) Term: **15 Years**

(21) Appl. No.: **29/630,611**

(22) Filed: **Dec. 21, 2017**

(51) LOC (11) Cl. **14-04**

(52) U.S. Cl.

USPC **D14/486**

(58) **Field of Classification Search**

USPC D14/485-495

CPC G06F 3/048-04897

(57) **CLAIM**

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof and form no part of the claimed design. The broken line text illustrates portions of the graphical user interface and forms no part of the claimed design.

1 Claim, 1 Drawing Sheet
